SKEWER

Alfred Farber, 20 W. 72nd St., New York, N.Y.

Filed Oct. 19, 1961, Ser. No. 67,156

Term of patent 3½ years

(Cl. D81—10)

FIG. 1

FIG. 2

FIG. 3

FIG. 4

FIG. 5

FIG. 1 is a side view of a skewer showing my new design;

FIG. 2 is a front view;

FIG. 3 is an end enlarged view from the right of FIG. 1;

FIG. 4 is an enlarged view, along the line 4-4 of FIG. 1; and

FIG. 5 is an enlarged cross-sectional view along the line 5-5 of FIG. 1.

I claim:

The ornamental design for a skewer, substantially as shown.
